UNITED STATES PATENT OFFICE.

JACOB G. SEEHORN, OF CANBY, OREGON, ASSIGNOR OF ONE-HALF TO D. V. TANT-LINGER, OF LAWTON, OKLAHOMA.

TRAIN-CONTROLLED SWITCH-OPERATING DEVICE.

Application filed May 27, 1924. Serial No. 716,196.

To all whom it may concern:

Be it known that I, JACOB G. SEEHORN, a citizen of the United States of America, residing at Canby, in the county of Clackamas and State of Oregon, have invented new and useful Improvements in Train-Controlled Switch-Operating Devices, of which the following is a specification.

The purpose of the invention is to provide a switch operating mechanism of simple, cheap and effective construction and adapted for operation to selectively close and open it through means under control of the engineer or motorman driving the train.

With this purpose in view the invention consists in a certain construction and combination of parts of which a preferred embodiment is illustrated without defining the limits of the invention.

Figure 1 is a plan view of a portion of a railroad track and connected switch showing the invention applied thereto.

Figure 2 is a section on the line 2—2 of Figure 1.

Figure 3 is a section on the line 3—3 of Figure 1.

Figure 4 is a perspective view of the forward end of the locomotive showing the train carried mechanism for operating the device.

Figure 5 is a perspective view of the car carried mechanism and the operating means therefor.

The invention contemplates a construction wherein the engineer or motorman of a train or car traversing the track such as that indicated at 1, may direct his train or car on to the branch or connected track 2 by the actuation of the switch point 3 from the cab.

To this end there is mounted in the road bed between the rails of the track 1 and between the switch points 3 a rotatable head 4 operatively connected with actuating rotatable heads 5 disposed between the rails of the track 1 and in advance of and behind the head 4, the operative connections consisting of flexible members 6 terminally secured to the heads 5 and encircling the head 4 and having their opposite terminals connected

with the switch points 3 as indicated at 7, the points being interconnected for simultaneous operation as in the usual practice the flexible members 6 are connected at diametrically opposite sides of the rotatable heads 5 and encircle the head 4 in the opposite direc-

tion, being connected with opposite switch points 3, so that in the rotation of the head 5 at one direction, the switch points will be shifted laterally to one side and in the direction will be shifted laterally to the other side, so that the branch 2 may be brought into or out of communication with the main track 1. The position of the switch point is indicated by a suitable signaling device 8 mounted on a rotatable standard 9 carrying near its base a spool 10 around which a flexible member 11 is wound, said flexible member being also carried around the rotatable head 4. Since but slight angular movement of the head 4 is necessary to effect the desired shifting of the switch points, whereas an angular movement of 90° is necessary to operate the signal, the diameter of the spool 10 is reduced below the diameter of the rotatable head 4 so that the necessary proportion of diameters is such that an angular movement of 90° takes place in the signal arm for a comparatively slight angular movement of the rotatable head 4.

In order that the switch points may be positively held in the positions to which they are moved by the operation of the heads 4 and 5, the former is provided with radial arms 12 for abutting engagement with the inner side faces of the switch points to hold them in their set positions, the one to establish communication throughout the main track and the other to establish communication between the main track and the branch 2.

Undue shock in the operation of the switch points is provided against by the inclusion in the flexible members 6, of coiled springs 13.

The rotatable heads 5 are designed for actuation by train carried means such as arms 14 swingingly mounted on the locomotive on opposite sides of the latter and have engagement respectively with radial arms 15 carried on the rotatable heads 5. If one arm 14 is lowered, it rotates the head 5 in one direction with the consequent movement of the switch points to effect their movements in the desired direction, reverse movement to the switch points being secured by the operation of the head 5 by the other arm which when lowered engages one of the radial arms 15 to turn the head in the opposite direction than formerly. It being essential that means be provided precluding the lowering

of both arms 14 at the same time, they are connected by flexible members 16 with a transverse rocker head 17 carried in the engine cab and pivotally mounted at a central point 18. The position of the rocker 17 transversely of the cab results in the elevation of both arms a sufficient distance to clear the rotary heads 5. Desiring to lower the one arm, the engineer grasps one of the handles 19 carried respectively at opposite ends of the rocker and moving that forward will permit the lowering of the arm 14 connected by the flexible member 16 with that end of the rocker, the other arm being obviously elevated further from the track bed. The provision of the rocker positively precludes the lowering of both arms at once but the direction in which the rocker is moved determines which arm 14 shall be lowered and dictates the direction in which the switch points will be moved.

Having described the invention, what is claimed as new and useful is:

1. In combination with a railroad switch, a rotary head mounted between the switch points, an actuating rotary head disposed in advance of the first said rotary head and provided with radial arms for engagement

by a car-carried element, and flexible connections between the second said rotary head and the switch points, said flexible connections traversing the first said rotary head, said first said rotary head being provided with radial arms for engagement with the inner faces of the switch points.

2. In combination with a railroad switch, a rotary head mounted between the switch points, an actuating rotary head disposed in advance of the first said rotary head and provided with radial arms for engagement by a car-carried element, flexible connections between both the said rotary heads, and operative connections between the second said rotary head and the switch points.

3. In combination with a railroad switch, a rotary head mounted between the switch points and provided with radial arms for engagement with the inner faces of the switch points, an actuating rotary head disposed in advance of the first said rotary head and adapted for actuation by a car-carried element, and operative connections between said rotary head.

In testimony whereof I affix my signature.

JACOB G. SEEHORN.
